UNITED STATES PATENT OFFICE.

THEIS F. BERNARD, OF DETROIT, MICHIGAN, ASSIGNOR TO FREDERICK M. EHEHALT,
OF DETROIT, MICHIGAN.

MECHANICAL DEVICE FOR GRINDING TWO CYLINDRICAL MACHINE PARTS AT THE SAME TIME.

1,367,522.

Specification of Letters Patent.

Patented Feb. 1, 1921.

Application filed March 22, 1920. Serial No. 367,837.

To all whom it may concern:

Be it known that I, THEIS F. BERNARD, a citizen of the United States, and residing at the city of Detroit, county of Wayne, and 5 the State of Michigan, have invented certain new and useful Improvements in Mechanical Devices for Grinding Two Cylindrical Machine Parts at the Same Time, and declare the following to be a full, clear, and 10 exact description of the same, such as will enable others skilled in the art to which it pertains to make use of the same, reference being had to the accompanying drawings, which form a part of this specification.

15 The objects of my invention are, to provide a means whereby two cylindrical pieces may be ground at the same time; to provide proper adjustment of the parts to the axis of the grinding wheel; and to grind 20 pieces of different diameters at the same time.

This is accomplished by mounting a secondary grinding spindle directly above the primary grinding spindle, both being driven 25 by a common power wheel so as to rotate in the opposite direction to that of the grinding wheel. The secondary spindle being mounted on an adjustable frame to allow the upper cylindrical part to be brought in contact with the grinding wheel, and with a horizontal adjustment to take care of the 30 various lengths of pieces to be ground.

It is a further object of the invention to 35 secure a device that is simple in construction, effective in its operation, and can be easily and accurately controlled and adjusted. These several objects are secured in the preferred form by the construction and arrangement of parts as are hereinafter 40 more fully described.

Similar parts are marked by similar numerals in all drawings.

Figure 1, is a front view of the grinder, showing the general arrangement of the assembled parts.

Fig. 2, is a top view showing arrangement of spindles and adjusting mechanism.

Fig. 3, is an end view showing the arrangement of the double drive from the common power wheel.

Fig. 4, is a sectional view, —AA— as is shown on Fig. 2, showing the arrangement of the adjustment on the secondary spindle.

Fig. 5, is a vertical section —BB—, as is

shown on Fig. 3 showing the double spindles and drive, with the adjustments of the tail centers to care for the variations in length of cylindrical pieces to be ground.

I will now describe more fully the working parts of the device, referring to the accompanying drawings and the marks thereon.

The entire device is mounted upon a swivel base 1, and 2, which are pivoted together at the center by pin 3. Both base plates are 65 to be securely clamped to the horizontal table of the grinding machine, by clamps at the end thereof, as is indicated in Fig. 1. At the power end of the grinder head, the upper base plate 2, carries a solid bearing 70 (4) thereon and securely fastened thereto. At the opposite end of the top base plate 2, is an adjustable bearing 5, which is securely clamped thereto by means of bolts 6, to allow for a general adjustment of the entire 75 head for grinding cylinders of various lengths. Mounted upon the stationary bearing 4, is an adjustable bearing 7, carrying a secondary driving spindle 8. Bearing 7 is pivoted to bearing 4 by means of a cylindrical sleeve 9 which passes through both bearings 4 and 7 and allows the latter to rock back and forth thereon. Bearing 4 also carries within the sleeve 9, the primary 80 grinding spindle 10, which is within and 85 splined to the hollow gear shaft 11. The keys 19 and 20 allow a horizontal adjustment of the driving spindle 10 and the driving center 12 by means of the adjusting nuts 14 and 15. Gear shaft 11 is securely fastened to gear 13 and driven by a common 90 power gear 16. Drive gear 16 is securely fastened to drive pulley 17 and rotates continuously therewith. Gear 16 and drive pulley 17 are mounted on a stub shaft 18 95 fastened in the adjustable bearing 7. The adjustable bearing 7 carries at the top the secondary driving spindle 8, which is within and splined to the hollow gear shaft 21. The keys 22 and 23 allow a horizontal movement of the secondary driving spindle 8 by 100 means of the adjusting nuts 24 and 25. Gear shaft 8 is fastened to drive gear 26 and driven by the common drive gear 16 and pulley 17. Both spindles 8 and 10 carry 105 within the end, driving center points 12 and 27. The center points 12 and 27 are fastened to driving spindles 8 and 10 by means

of a taper and a key, and revolve continuously therewith. The cylindrical work may be driven by means of a socket dog extending from the irregular collar 28 on the driving centers 12 and 27 to the irregular head on the cylindrical work. Mounted upon the adjustable bearing 5 is an adjustable arm 29, which is pivoted to bearing 5 by means of a cylindrical sleeve 30 and passing through both bearing 5 and arm 29, allowing arm 29 to rotate thereon for adjustment. Mounted on arm 29 and rotating about the same center, is a secondary adjustable bearing 35. Bearing 35 is supported by an arm 15 carrying a secondary micrometer adjusting screw 36, the lower end of said screw resting upon bearing 29, and any movement of the screw will give an added adjustment to bearing 35, tilting the tail centers either 20 backward or forward and into perfect alignment with the lower primary grinding spindle. Bearing 35 also carries an adjusting micrometer indicator pin 51 set in the casting and supported by a coil spring 52. The 25 top end of pin 51 serves as a zero indicator for the micrometer readings, and the upward pressure of the spring 52 acts as a brake on the micrometer wheel 36 thus preventing rotation thereof. Bearing 35 carries at the top an adjustable sleeve 37 which in turn carries a tail center 38. Bearing 29 at the bottom also carries an adjustable sleeve 40, which in turn carries a tail center point 41. Both sleeves 37 and 40, have a 30 horizontal movement in the main bearings 35 and 29, caused by the rotation of pinion 42, as lever 43 is raised or lowered. The hollow sleeves 37 and 40 carry therein a tension spring to hold the centers in place and 35 tight against the work. Inside sleeves 37 and 40 are also stationary blocks 46 and 47 for holding the adjusting springs 44 and 45 in place, and which are fastened to the main bearings 29 and 35, by means of small pins 48 and 49 passing through both block and bearing, and the slotted ways in the slides of the movable sleeves 37 and 40. Pinion 42 rotates about its axis 50 and engages teeth on both sleeves 37 and 40, but axis 50 slides 45 in a horizontal slot in bearing 35. A movement of the handle 43 downward therefore rocks pinion 42 about its lower edge where it engages in the teeth of the sleeve 40, causing the axis 50 to slide horizontally in 50 slot and also a horizontal movement of the sleeve 37 to release the center point 38 from the cylindrical work. On release of the handle 43, the tension spring 44 will return the center point and sleeve 37 to place. An 55 upward movement of the handle will likewise release the lower center 41 from the lower work. At the outer end of arm 29 is an adjusting slide 31 securely clamped thereto by means of a cap screw 32, and 60 providing means for a horizontal adjust-

ment of the main bearing 5. Slide 31 is also clamped to the outer end of the adjustable bearing 7 by means of a slot and a cap screw 33, thus giving rigidity to the two adjustable bearings 7 and 29, causing them to 70 act as one frame in a solid and rigid manner. Bearing 7 carries a micrometer adjusting wheel 34 which is threaded therein and passes through the arm of bearing 7, and the lower end of which rests on the top 75 of the base plate 2. Any turning of the micrometer screw will either raise or lower the arm on bearing 7, which being connected to bearing 29 by means of the clamped slide 31, will work as a solid frame and thus rock 80 both bearings as one unit and move the secondary grinding spindle to and from the grinding wheel to make the proper adjustments for the various diameters of the cylindrical work. Bearing 7 also carries a 85 micrometer pin 53, supported by a coil spring 54. This pin like pin 51 serves as a zero indicator, also the pressure of spring 54 prevents the rotation of the micrometer screw 34. 90

I do not wish to confine myself to the exact construction as herein described, but merely give this as a preferred form of construction.

Having fully described my device herein, what I claim as my invention and desire to 95 secure by Letters Patent is:

1. In a double grinding head for grinding two cylindrical pieces at the same time, in combination with a horizontally moving table of the grinding machine and the rotating grinding wheel, of a base fixedly attached to the horizontally moving table, a secondary base swiveled thereto, of a primary rotating grinding spindle mounted thereon, with means for driving same, a secondary rotating grinding spindle mounted 100 above the primary spindle, means for supporting said secondary spindle, means for adjusting and alining secondary spindle, and means for driving same and causing it to 105 rotate against the grinding wheel.

2. In a device of the character described, in the combination with the horizontally moving table of the grinding machine and the rotating grinding wheel, of a base fixedly 115 attached to the horizontal table, a secondary base swiveled thereto, a primary grinding spindle mounted thereon, means for turning same, a secondary grinding spindle mounted above the primary spindle, means 120 for adjusting same, a hollow cylindrical sleeve mounted therein with means for a horizontal adjustment thereof, and means for driving the spindle against the rotating grinding wheel.

3. In a device of the character described, in combination with the horizontal table of the grinding machine and the rotating grinding wheel, of a double swiveled base fixedly attached to the horizontal table, a primary

- grinding spindle mounted thereon, means for turning same, a secondary grinding spindle mounted above the primary spindle, means for adjusting same, a hollow cylindrical sleeve mounted therein, a center point and means for fastening same, a driving casing outside the cylindrical sleeve and connected thereto by sliding keys, a gear attached to the driving casing, a common gear attached to the main pulley, means for driving the pulley, gear, casing and secondary spindle, and means for a horizontal adjustment of the cylindrical sleeve and center-point.
4. A device of the character described in combination with the horizontal table of a grinding machine and the rotating grinding wheel, of a base fixedly attached to the horizontal table, a secondary base swiveled there- to, a stationary bearing mounted on top of said base, a primary grinding spindle, means for turning same, a secondary grinding spindle with means for turning same, and placed above the primary spindle in an adjustable bearing mounted thereon, on the driving end of the spindle, a stationary bearing, a cylindrical sleeve therein to pivot the adjustable bearing on, thus allowing the upper spindle to rock about the center of the lower spindle and adjust to the surface of the grinding wheel.
5. In a machine of the character described in combination with a horizontally moving table of a grinding machine and the rotating grinding wheel, of a compound base fixedly attached to the horizontal table of the grinder, of a primary spindle mounted thereon and supported by a stationary bearing attached to the base, a hollow sleeve in the driven end of the spindle, a center point securely fastened thereto rotates with the sleeve, means for a horizontal adjustment of the sleeve, a driving casing outside the cylindrical sleeve and connected thereto by sliding keys, a gear secured to the driving casing, a power gear attached to a driving pulley, and means for driving same.
6. In a device of the character described in combination with the horizontally moving table of the grinding machine and the rotating grinding wheel, of a compound base fixedly attached to the horizontal table, a primary and secondary grinding spindle mounted thereon, means for driving the same, a sliding adjustable bearing for the dead centers of the primary and secondary grinding spindles mounted on the main base, and for the purpose of adjusting the distance between the center points for long or short work, and means for adjusting the sliding bearing.
7. In a device of the character described in combination with the horizontally moving table of the grinding machine and the rotating grinding wheel, of a compound swiveled base securely attached to the horizontal table, a primary and secondary grinding spindle mounted thereon, means for driving both spindles, a sliding tail bearing connected to the main base, an adjusting arm pivoted to the main bearing by means of a hollow cylinder, means of connecting said adjusting arm with the adjustable bearing of the secondary driving spindle thus making the two a solid frame.
8. In a device of the character described in combination with the horizontally moving table of the grinding machine and the rotating grinding wheel, of a base fixedly attached to the horizontal table, a secondary base mounted thereon and swiveled therewith by a center pin, a primary and a secondary grinding spindle mounted thereon, means for driving both spindles, a sliding tail bearing connected to the main base, an adjustable arm pivoted to the main bearing by means of a hollow cylinder, means of connecting said adjusting arm with the adjustable bearing of the secondary driving spindle and thus making the two a solid frame, a hollow sleeve with a horizontal adjustment, a center tail point for the primary driving spindle, a coil spring within the hollow sleeve to hold the tail center in place, a stationary block within the sleeve to support the coil spring, means for holding the block in place, and means for causing the horizontal movement of the sleeve to release the tail center from the work.
9. In a device of the character described in combination with the horizontally moving table of the grinding machine and the rotating grinding wheel, of a compound swiveled base securely attached to the horizontal table, a primary and a secondary grinding spindle mounted on said base, means for driving both spindles, a sliding tail bearing connected to the main base, an adjustable arm pivoted to the main bearing by means of a hollow cylinder, means for connecting the adjusting arm with the adjustable bearing of the secondary driving spindle, a secondary adjustable arm mounted on top of the adjustable frame arm and pivoted about the same center of the sliding tail bearing, a hollow sleeve with a horizontal adjustment, a tail center for the secondary grinding spindle held within said sleeve, a coil spring within sleeve, a stationary block within said sleeve to support the coil spring, means for holding block in place, and means for causing a horizontal movement of said sleeve to release the secondary tail center from the work.
10. In a device of the character described in combination with the horizontally moving table of the grinding machine and the rotating grinding wheel, of a compound base fixedly attached to the horizontal table, a primary and a secondary grinding spindle

mounted thereon, means for driving both spindles, a sliding adjustable bearing connected to the main base, an adjustable arm pivoted thereto and connected with the adjustable bearing of the secondary driving spindle making it a solid frame but with means for the adjustment thereof, a secondary adjusting arm mounted on top of the adjustable frame arm and both pivoted to the sliding bearing by means of a cylindrical sleeve, a movable sleeve inside the cylinder carrying the tail center point for the primary grinding spindle, a movable sleeve within the adjustable arm carrying the tail center for the secondary grinding spindle, a pinion gear engaging the gear teeth on the outside of both the tail center sleeves; the center of the pinion sliding in a slot in the adjustable arm casting, a lever for rotating said pinion for releasing either of said tail centers from the work, a spot in said adjustable arm for removing the pinion and adjusting the tail center sleeves to different relative positions.

11. In a device of the character described in combination with the horizontally moving table of the grinding machine and the rotating grinding wheel, of a compound swivel base securely attached thereto, a primary and a secondary grinding spindle mounted thereon, means for driving both of said spindles, a sliding tail bearing connected to the main base, an adjustable arm pivoted to the main bearing by means of a

hollow cylinder, means for connecting said 35 adjusting arm with the adjustable bearing of the secondary driving spindle and thus making the two a solid frame, a micrometer adjusting screw connected to this frame and resting on the main base, and means for 40 holding the screw from turning.

12. In a device of the character described in combination with the horizontally moving table of the grinding machine and the rotating grinding wheel, of a compound swivel base securely attached to the horizontal table, a primary and a secondary grinding spindle mounted thereon, means for driving both spindles, a sliding tail bearing connected to the main base, an adjustable arm 45 pivoted to the main bearing, means for connecting said adjustable arm with the adjustable bearing of the secondary driving spindle, a micrometer adjusting screw connected to the main frame, a pressure plug set in the 50 said frame bearing upward against the edge of the micrometer wheel by means of the coil spring under the plug, by turning the micrometer screw the frame is raised or lowered to adjust the upper secondary grinding 55 spindle to the grinding wheel.

In testimony whereof I, THEIS F. BERNARD sign these specifications.

THEIS F. BERNARD.
